UNITED STATES PATENT OFFICE.

EDWARD H. TATE, OF MALDEN, MASSACHUSETTS.

MOP HOLDER.

Application filed May 31, 1924. Serial No. 716,919.

To all whom it may concern:

Be it known that I, EDWARD H. TATE, a citizen of the United States, residing at Malden, in the county of Middlesex and State of Massachusetts, have invented new and useful Improvements in Mop Holders, of which the following is a specification.

This invention relates to a mop-holder comprising a sheet metal head including a marginal flange, usually of triangular form, on which the flexible neck portion of a mop may be seated, and a bottom from which the flange projects, and a handle-receiving sleeve having a pintle socket and hinged to the bottom, so that an elongated handle engaged with the sleeve may assume various inclinations relative to the head.

The object of the invention is to reduce to a minimum the number of parts required to produce a holder which includes a handle-receiving sleeve hinged to the head.

I accomplish this object by making elements of the hinge connection integral with the head, so that the holder comprises only two parts or pieces, in addition to the sleeve and its pintle socket, one of said parts being the head, and the other a pintle.

Of the accompanying drawings forming a part of this specification,—

Figure 1 is a perspective view of the one-piece sheet metal head.

Figure 2 is a section on line 2—2 of Figure 1.

Figure 3 is a section on line 3—3 of Figure 1.

Figure 4 is a top plan view, showing the handle sleeve hinged to the head.

Figure 5 is a section on line 5—5 of Figure 4.

Figure 6 is a section on line 6—6 of Figure 4.

Figure 7 is a side view, showing the head and a flexible mop attached thereto.

Figure 8 is a view similar to Figure 6, showing a modification.

The same reference characters indicate the same parts in all of the figures.

The sheet metal body including in one piece, a marginal flange 12, a bottom 13, and hinge elements, is shown in perspective by Figure 1. The flange 12 projects outward from the bottom 13, and is substantially triangular. The bottom 13 is provided with two alined outwardly projecting spaced apart socket bosses 15 and 16, and with transverse parallel ridges 14, forming oppo-

site sides of a channel 14^a, extending between the bosses. Said bosses are adapted to receive a hinge pintle 17, and the channel 14^a is adapted to receive a side portion of a hinge socket 18 interposed between the bosses and formed on a handle-engaging sleeve 19.

The socket 18 is placed on the channel 14^a and located thereby in alinement with the socket bosses, preparatory to receiving the hinge pintle.

The pintle 17 is a cylindrical rod of greater length than the hinge socket 18. The boss 16 as originally formed, is internally unobstructed from end to end, as shown by Figure 2, so that the pintle may be inserted in its outer end, as indicated by dotted lines in Figure 2, and moved into the hinge socket 18 and the socket boss 15, as shown by Figure 6.

After the pintle is in place in the socket bosses and hinge socket, the outer end of the socket boss 16 is provided with a stop 16^a (Figure 6), preventing the withdrawal or outward movement of the pintle from the hinge socket 18. Said stop is provided by indenting or inwardly bending a portion of the boss between its ends, thus forming the inclined portion or stop 16^a bearing on the outer end of the pintle. The boss 16, preferably extends to the flange 12, as shown by Figures 1, 2, 4 and 6, and its outer end forms a pintle-receiving opening in the flange. If desired, however, a shorter boss 16^b may be provided, as shown by Figure 8, in which case, the flange 13 is provided with a pintle-receiving opening 24 in alinement with the boss. The pintle stop may be provided by inwardly bending a portion of the outer end of the boss 16^b, to form a lip 16^c, bearing on the outer end of the pintle, as shown by dotted lines in Figure 8.

I provide means for limiting the insertion or inward movement of the pintle, and to this end I preferably provide the socket boss 15 with a closed end 15^a, constituting a stop limiting the movement of the pintle in the direction in which it was inserted. If desired, however, the socket boss 15 may be open from end to end, as shown by Figure 8, in which case the pintle is made long enough to project from said boss and abut against the flange 12.

It will now be seen that a three-part holder is provided, composed of the one-piece body having the socket bosses 15 and

16, the handle-receiving sleeve having the hinge socket 18, and the hinge pintle. It will also be seen that a hinge connection is established between the body and the handle sleeve, by the operation of assembling the three parts, said operation consisting in placing the hinge socket between the socket bosses, inserting the pintle, and finally forming the stop 16^a or 16^c. The channel 14^a
5 locates the socket 18 in alignment with the bosses 15 and 16, so that the pintle may be easily inserted. The time and labor required to produce the holder are, therefore,
10 reduced to a minimum, and a durable holder
15 is provided at a nominal expense.

The usual flexible mop neck 21, from which the mop threads 22 depend, is seated on the outer surface of the flange 12, and may be secured thereto by rivets 23, as
20 shown by Figure 7, the flange being provided with rivet holes 24. One of the ridges 14 constitutes a stop to limit the swinging movement of the handle sleeve 19 in the direction of the arrow in Figure 5. The
25 shank of the handle sleeve 19 abuts against this stop, as indicated by dotted lines in Figure 5.

I claim:

1. A mop-holder comprising a one-piece
30 sheet metal body including a marginal flange, provided in one of its sides, with a

pintle-receiving opening, and a bottom, provided with aligned outwardly projecting spaced apart socket bosses, a handle-receiving sleeve having a pintle socket registering with the socket bosses; and a hinge pintle inserted in said opening and socket bosses and said pintle socket, one of the socket bosses having an inwardly bent portion bearing on the outer end of the pintle and 40 constituting a stop preventing the withdrawal of the pintle, means being provided for limiting the insertion of the pintle. 35

2. A mop-holder comprising a one-piece sheet metal body including a marginal flange, provided in one of its sides, with a pintle-receiving opening, and a bottom provided with aligned outwardly projecting spaced apart socket bosses, a handle-receiving sleeve having a pintle socket registering 45 with the socket bosses; and a hinge pintle inserted in said opening and socket bosses and said pintle socket, one of the socket bosses having an inwardly bent portion bearing on an end of the pintle and 50 constituting a stop preventing the withdrawal of the pintle, the other socket boss having a closed end limiting the insertion of the 55 pintle.

In testimony whereof I have affixed my 60 signature.

EDWARD H. TATE.
